PATENTED MAY 31 1870

United States Patent Office.

PIETRO CINQUINI, OF WEST MERIDEN, CONNECTICUT, ASSIGNOR TO
BRADLEY & HUBBARD, OF SAME PLACE.

Design No. 4,086, dated May 31, 1870.

DESIGN FOR A LAMP-BRACKET.

The Schedule referred to in these Letters Patent and making part of the same.

To all whom it may concern:

Be it known that I, PIETRO CINQUINI, of West Meriden, in the county of New Haven and State of Connecticut, have invented a new Design for Lamp-Bracket; and I do hereby declare the following, when taken in connection with the accompanying drawings and the letters of reference marked thereon, to be a full, clear, and exact description of the same, and which said drawings constitute part of this specification, and represent, in

Figure 1, a front view of the socket, and in

Figure 2, a side view of the bracket.

This invention relates to a design for a bracket for supporting kerosene-lamps, but is alike applicable for gas-burners.

In fig. 1 a front view of the socket is shown. The

socket is secured to the wall to receive the pintle *a* of the bracket, so that the bracket will swing to the right or left, and in such brackets as require a reflector, I arrange a stud, *d*, and the ring or support for the lamp-body is applied at *f*.

The design and configuration of the bracket are clearly shown in fig. 3.

I claim as my invention—

The design for bracket, as clearly shown in the accompanying photographic illustration, and with or without the reflector support or socket.

PIETRO CINQUINI.
